INVENTOR
CHARLES N. CORYELL
BY *Albert M. Austin*

ATTORNEY

UNITED STATES PATENT OFFICE.

CHARLES N. CORYELL, OF MAMARONECK, NEW YORK.

LIPSTICK CONTAINER.

Application filed February 23, 1924. Serial No 694,558.

To all whom it may concern:

Be it known that I, CHARLES N. CORYELL, a citizen of the United States, and resident of Mamaroneck, in the county of Westchester and State of New York, have invented certain new and useful Improvements in Lipstick Containers, of which the following is a specification.

The present invention relates to holders for lipsticks and the like and special objects of the invention are to provide a device of this character which will be of simple, inexpensive, light construction; attractive appearance; made up of but few parts, capable of being readily assembled and operable with a quick easy action to positively project and retract the lipstick or other contained element.

The accompanying drawing forming part of this specification illustrates a practical embodiment of the invention, wherein the foregoing and other objects are attained through a novel construction, combination and relation of parts as hereinafter set forth.

Figure 1 is a side view of the invention as embodied in a lipstick holder showing the same in the closed condition.

Figure 2 is a vertical sectional view of the device.

Figure 3 is a side view showing the cover opened and the stick projected.

Figure 4 is a cross sectional view on substantially the plane of line 4—4 of Figure 2.

Figure 5 is a broken rear view of the hinge construction for the cap.

Figure 6 is a broken detail view of the hinge pintle.

Figure 7 is a detail view of the helical screw member of the device.

Figure 8 is a fragmentary detail view showing the manner in which the outer casing and sleeve are rotatably confined to the inner sleeve by the overturned flange at the mouth of the latter.

The carrier for the lipstick, which in this instance constitutes the shiftable element of the device, is slidably confined within a tubular guide or sleeve 10 and is shown in the form of a cup shaped member 11 held to a straight sliding movement within the guide sleeve by a projecting pin 12 operating in a longitudinally extending slot 13.

The pin 12 is of special construction in that it is made of a single piece of spring wire having a straight portion to project through an opening 14 in the side of the car-

rier and provided with a bent portion 15 of partly circular form of "button hook" shape to form a spring head yieldingly fitting inside the carrier. This pin is secured within the carrier by compressing and forcing it down against the closed bottom of the carrier and turning it, if necessary, to bring the point of the same into register with the opening 14; whereupon the pin will snap into final position with the straight portion of the same projecting from the carrier and the coiled portion frictionally gripping the inner wall of the cup.

The lower closed end of the tubular guide 70 is shown as enlarged to provide an external annular shoulder 16 and to serve as an operating knob or head 17. A shoulder effect is also shown provided at the upper end of this guide by constructing it with an outwardly flared rim 18.

Engaged about the guide sleeve in relatively rotatable fashion and confined between the upper and lower shoulders described is a cam or screw sleeve 19 and a 80 casing sleeve 20, the first having a helical slot 21 receiving the projecting end of pin 12 and held fast to the casing sleeve 20 by its frictional engagement within the same.

A practical method of constructing the 85 screw sleeve is to make the same of a strip of flat spring material such as designated 22 in Figure 7, wound into helical form with spaces between adjacent convolutions to provide the continuous helical screw slot. In 90 addition to the advantages of simplicity and inexpensiveness, this construction gives a spring tension which causes this element to automatically fit and securely engage itself within the casing. The desired amount of 95 spring tension may be provided by a proper selection of material and by winding the strip sufficiently larger than the inside diameter of the casing.

A hinged cap 23 is shown provided for 100 closing the upper open end of the holder, said cap being illustrated as frictionally engaging down over the upper end of the casing and as yieldingly held closed by snapping over a lug or projection 24 forced 105 out of the side of the casing.

The cover is mounted by a novel hinge construction comprising a pintle wire 25 encircled at its intermediate portion by a knuckle extension 26 dependent from the 110 rear edge of the cover, said knuckle extension fitting into a slot 27 in the upper

edge of the casing and the casing having a bead 28 about the same forming sockets at the opposite sides of notch 27 to take the curved end portions of the pintle wire. With this construction only a short pintle wire is necessary, since the same is firmly held within the bead by reason of its straight intermediate portion within the knuckle 26 and its curved or bent end portions within the bead, the end of the helical sleeve inside the casing acting as a retainer to positively secure such end portions of the wire in place.

A special and important feature of the invention is that the parts can be easily assembled without soldering or the use of special tools, and further, that the several parts are secured together in their proper relations by the simple acts of assembling the same. Thus the guiding and actuating pin is secured within the carrier by simply forcing the same down into the cup of the carrier and positioning it so that the point of the pin will spring out through the opening provided just above the bottom of the carrier. The carrier may then be engaged within the guide tube by entering it within the same and forcing back the point of the pin until it snaps into the straight guide slot. The spirally twisted sleeve because of its spring character is easily slipped over the flange end of the guide tube and after it is turned to locate the helical slot therein over the projecting portion of the pin and compressed somewhat, it is an easy matter to slip the casing on over the helical tube and force it down until the upper end of the same snaps under the shoulder provided by the flanged rim 18. Before the casing is forced all the way on, the hinge pintle should be engaged in its sockets so that as the casing snaps into place, the ends of the hinge pintle will be brought against the outer surface of the helical sleeve. The slot provided in the upper edge of the casing to receive the hinge knuckle of the cap provides the amount of resiliency necessary to enable the upper end of the casing sleeve to pass over the flanged end of the guide sleeve and snap into position underneath the same.

The parts of the device are few, and of simple construction, and it will be seen also that assembling costs are reduced to a minimum. The device is compact, of pleasing appearance and susceptible of ornamentation to suit the taste. The action is positive and easy, only a slight effort being required to effect the relative rotation between the casing and guide sleeve necessary to cause the carrier to travel longitudinally in one direction or the other within the guide sleeve. The spring character of the helical sleeve prevents rattling or looseness of parts and tends to yieldingly retain the members in the positions to which they may be ad-

justed. By its frictional engagement within the casing the spring sleeve becomes in effect a part of said casing, providing the same with an internal helical shoulder which because of its angular relation to the straight slot in the inner sleeve produces the desired longitudinal travel of the carrier upon relative rotation of the casing and inner sleeve or guide.

What I claim is:

1. In a holder of the character disclosed, relatively rotatable tubular members having angularly related shoulders to produce longitudinal travel of an element engaged with said shoulders upon relative rotation of the members, a longitudinally shiftable part guided by one of said tubular members and a pin having a coiled head portion frictionally engaged with a wall of said longitudinally shiftable part and a portion projecting from said coiled head into engagement with the relatively inclined shoulders on the two relatively rotatable tubular members.

2. In a holder of the character disclosed, an outer casing containing an internal helical shoulder, a slotted tubular guide within said casing having at one end an enlargement providing an operating head and forming also a stop shoulder for engagement with the end of the casing, the opposite end of said inner tubular guide having an outwardly turned flange engaging over the opposite end of the casing, whereby said tubular guide is rotatably confined within the casing and the end of the casing is protected by the overstanding flange and a carrier in the tubular guide having a pin projecting through the slot in the guide into engagement with the helical shoulder carried by the casing.

3. In a holder of the character disclosed, a tubular slotted guide, a slotted sleeve surrounding said guide, a casing fixedly engaged over the slotted sleeve and confined in relatively rotatable relation about the tubular guide, a shiftable member within the guide and a spring pin having a coiled head portion confined to said shiftable member and a straight portion projecting from said shiftable member through the slots in the guide and sleeve respectively.

4. In a holder of the character disclosed, a slotted tubular guide, a slotted sleeve surrounding said guide, a casing fixed over said sleeve and confined in relatively rotatable relation over the guide, a hollow carrier within the guide provided with an opening in one side and a spring pin having a coiled portion confined within said hollow carrier and a projecting portion extending through the opening in the side of the carrier into the slots in the guide and sleeve respectively.

5. In a holder of the character disclosed, guide and sleeve members having angularly related slots whereby relative rotation of

- said members will produce longitudinal travel of an element engaged in said slots, a hollow carrier within the guide member and a pin having a coiled portion confined 5 in said carrier and a projecting portion extending from the carrier through the slots in the relatively rotatable members.
6. In a holder of the character disclosed, relatively rotatable concentric members having 10 slots intersecting on an angle to produce longitudinal travel of an element engaged in said slots upon relative rotation of such members, a longitudinally shiftable part guided by one of said members and a pin 15 having a coiled head portion frictionally engaged with a wall of said part and a portion projecting from the part into the relatively intersecting slots in the rotatably related members.
- 20 7. In a holder of the character disclosed, a tubular casing, a spring strip twisted helically into tubular form with space between the convolutions to leave a helical slot, said spring strip being seated substantially full 25 length within the casing and engaged by its spring tension with the inner wall of the casing, whereby said coiled strip is fixed in definite relation within the casing and held positively to prevent any uncoiling action 30 of the strip and to prevent variations in the space between the convolutions, means confining the casing carrying the coiled strip on the inner wall of the same in definite relatively rotatable relation to the inner tubular 35 guide and a longitudinally shiftable member within the guide having a pin operating in the slots described.
8. In a holder of the character disclosed, relatively rotatable concentrically disposed 40 tubular members having relatively inclined shoulders, the inner tubular member having a stop shoulder at one end engaged by the end of the outer tubular member to limit movement of said outer member in one 45 direction, the opposite end of said inner tubular member being open and flanged outwardly over the adjoining end of the outer tubular member, whereby said outer tubular member is confined in relatively 50 rotatable relation upon said inner tubular member and a carrier within the inner tubular member having a lug engaged with the angularly related shoulders of the two members.
- 55 9. In a holder of the character disclosed, relatively rotatable concentrically disposed tubular members having relatively inclined shoulders, the inner tubular member having a stop shoulder at one end engaged by the 60 end of the outer tubular member to limit movement of said outer member in one direction, the opposite end of said inner tubular member being open and flanged outwardly over the adjoining end of the outer 65 tubular member, whereby said outer tubular member is confined in relatively rotatable relation upon said inner tubular member and a carrier within the inner tubular member having a lug engaged with the angularly related shoulders of the two members.
- 70 10. In a holder of the character disclosed, relatively rotatable concentrically disposed tubular members having relatively inclined shoulders, the inner tubular member having a stop shoulder at one end engaged by the end of the outer tubular member to limit movement of said outer member in one direction, the opposite end of said inner tubular member being open and flanged outwardly over the adjoining end of the outer tubular member, whereby said outer tubular member is confined in relatively rotatable relation upon said inner tubular member and a carrier within the inner tubular member having a lug engaged with the angularly related shoulders of the two members, the outer tubular member being of a springy nature and a casing forced over 75 said springy outer member to compress the same upon the inner tubular member and whereby said casing is frictionally secured upon the outer tubular member so as to remain fixed thereto in the relative rotation of the inner and outer tubular members.
- 80 11. A combination as in claim 2 in which the helical shoulder carried by the casing is provided by a spring strip twisted in the form of a helix and held in the casing by its spring engagement with the inner wall of the casing.
- 85 12. In a holder of the character disclosed, relatively rotatable concentric tubular members having relatively inclined slots, a carrier guided in the inner tubular member and having a lug operating in said slots, said inner tubular member having a finger hold at one end providing an external shoulder and an outwardly turned flange at the opposite end, a casing surrounding the outer tubular member and engaging at its opposite ends the shoulder and the outwardly turned flange of the inner member, whereby the casing and inner member are rotatably secured together and held against longitudinal separation, the outer tubular member being formed of spring material 90

- 130

- and being tensioned against the inner wall of the casing, whereby said casing and outer member are fixed with respect to each other.
13. In a holder of the character disclosed, 5 a slotted tubular member having an end enlarged to provide an operating head and open at the opposite end and there provided with an outwardly flanged rim, a casing held relatively rotatably on said tubular 10 guide between the head and flanged portions of the same, an internal helical member carried by said casing and a carrier within the tubular guide having a pin extending through the slot in the guide into engagement with the helical shoulder.
14. In a holder of the character disclosed, 15 a slotted tubular guide having an end enlarged into an operating head and open at the opposite end, a sleeve engaged over the tubular guide and having a slot inclined relatively to the slot in the tubular guide, said sleeve being held against expansion by the head at one end of the guide and the guide having an out-turned flange at its 20 open end engaged over the end of the sleeve to confine said sleeve on the guide in relatively rotatable relation and a carrier in the guide having a pin operating in the slots in the guide and sleeve respectively.
15. In a holder of the character disclosed, 25 a casing having an annular bead near one end and a notch extending from such end to the bead, a cap having a hinge knuckle operable in said notch and a pintle wire extending through said knuckle and having its 30 ends seated within the bead at opposite sides of the notch.
16. In a holder of the character disclosed, 35 a casing having an annular bead near one end and a notch extending from such end to the bead, a cap having a hinge knuckle operable in said notch, a pintle wire extending through said knuckle and having its ends seated within the bead at opposite sides 40 of the notch and a sleeve within the beaded
- portion of the casing overlying the ends of the pintle wire and thereby confining the same within the bead.
17. In a holder of the character disclosed, 45 a slotted tubular guide having a closed end enlarged to form an annular shoulder and having its opposite end open and provided with an out-turned flange, a slotted spring sleeve freely engageable over the open end of the tubular guide, a carrier within the guide 50 having a pin operable within the slots in the guide and sleeve, a casing passable over the guide and spring sleeve to bring the forward end of the same into engagement with the annular shoulder, the opposite end of said casing being notched to enable the same to spring over the flange of the guide and snap into position behind the same.
18. In a holder of the character disclosed, 55 a slotted tubular guide having a closed end enlarged to form an annular shoulder and having its opposite end open and provided with an out-turned flange, a slotted spring sleeve freely engageable over the open end of the tubular guide, a carrier within the 60 guide having a pin operable within the slots in the guide and sleeve, a casing passable over the guide and spring sleeve to bring the forward end of the same into engagement with the annular shoulder, the opposite end of said casing being notched to enable the same to 65 spring over the flange of the guide and snap into position behind the same.
19. In a holder of the character disclosed, 70 a slotted tubular guide having a closed end enlarged to form an annular shoulder and having its opposite end open and provided with an out-turned flange, a slotted spring sleeve freely engageable over the open end of the tubular guide, a carrier within the 75 guide having a pin operable within the slots in the guide and sleeve, a casing passable over the guide and spring sleeve to bring the forward end of the same into engagement with the annular shoulder, the opposite end of said casing being notched to enable the same to 80 spring over the flange of the guide and snap into position behind the same, said casing having internal sockets provided at the opposite sides of the notch therein, a cover having a hinge knuckle operable in said notch and a pintle wire extending through said knuckle having its ends seated in the sockets at opposite sides of the notch and held in such relation by 85 the spring cylinder within the case.

Signed at New York, in the county of New York and State of New York, this 20th day of February, A. D. 1924.

CHARLES N. CORYELL.

DISCLAIMER

1,504,217.—*Charles N. Coryell*, Mamaroneck, N. Y. LIPSTICK CONTAINER. Patent dated August 12, 1924. Disclaimer filed January 23, 1935, by the assignee, *Scovill Manufacturing Company*.

Hereby enters this disclaimer to that part of the claim in said specification which is in the following words, to wit:

“9. In a holder of the character disclosed, relatively rotatable concentrically disposed tubular members having relatively inclined shoulders, the inner tubular member having a stop shoulder at one end engaged by the end of the outer tubular member to limit movement of said outer member in one direction, the opposite end of said inner tubular member being open and flanged outwardly over the adjoining end of the outer tubular member, whereby said outer tubular member is confined in relatively rotatable relation upon said inner tubular member and a carrier within the inner tubular member having a lug engaged with the angularly related shoulders of the two members, the outer tubular member being of a springy nature and a casing forced over said springy outer member to compress the same upon the inner tubular member and whereby said casing is frictionally secured upon the outer tubular member so as to remain fixed thereto in the relative rotation of the inner and outer tubular members.”
